GEORGE F. SMITH, OF PHILADELPHIA, PENNSYLVANIA.

Letters Patent No. 66,995, dated July 23, 1867.

IMPROVEMENT IN VENETIAN BLINDS.

The Schedule referred to in these Letters Patent and making part of the same.

TO ALL WHOM IT MAY CONCERN:

Be it known that I, GEORGE F. SMITH, of the city of Philadelphia, in the State of Pennsylvania, have invented a new and useful Improvement in Venetian Blinds; and I do hereby declare that the following is a full, clear, and exact description of the construction and operation of the same, reference being had to the accompanying drawings, making a part of this specification, in which—

Figure 1 is a front view of a Venetian blind, as suspended in a window-frame, and showing my improvement applied thereto, the face-board of the blind being removed for the purpose; and

Figures 2, 3, and 4, enlarged transverse sections of parts of fig. 1—

Like letters of reference indicating the same parts when in the different figures.

My invention consists in the application, as hereinafter described; of a roller in combination with flat take-up bands and a suspended operating-cord, for the purpose of raising and lowering the slats of a Venetian blind. And my invention also consists, in combination with the subject-matter of the preceding paragraph, in the application of a ratchet-wheel, and a jointed, gravitating lever-pawl and brake; with a suspended end, as hereinafter described, for the purpose of controlling the gravitating tendency of the elevated slats, and securing them at any height that may be required.

Referring to the drawings, A is the roller; B B, the flat take-up bands; C, the suspended cord for raising the blind; D D, the slats of the blind; E, the gravitating lever-pawl; F, the brake-bar; G, the ratchet-wheel, (shown by dotted lines in fig. 2;) H, the suspended cord for operating the pawl-lever; and I the supporting-bar of the whole. The roller A turns upon axes fixed in its ends, and has two deep rectangular recesses a' a' cut uniformly around in its periphery, to receive the two respective take-up bands B B when wound up. The bands B B are of tape or other thin, flat, flexible fabric of like uniform thickness, and about half an inch wide, more or less. They are applied by passing them up on the rear side of the roller A, and tacking them fast in their respective grooves a' a', so as to extend or hang down therefrom through suitable square holes made in the slats D, to the lowest one of which latter they are fastened, (see the dotted lines in fig. 1,) the said slats being supported in flexible "ladders," K K, attached by the upper slat to the supporting-bar I by flat bands resting on friction-rollers, so as to operate in the usual manner for turning the slats. The operating-cord C has a tassel attached, and is fastened so as to hang from the front side of the roller A down in front of the blind, (see figs. 1 and 4.) On the opposite end of the roller A the ratchet-wheel G is fixed, and one of the axes of the roller projects therefrom and bears in a small upright, l. The pawl-lever E has its rear end jointed so as to permit the said end to be raised by the teeth of the ratchet-wheel G without raising the lever E, when the roller A is caused to be rotated by one's pulling on the cord C, but so that when left to itself it will fall between the teeth of the ratchet-wheel, and thus prevent the roller from being rotated in an opposite direction by the weight of the slats D, the said lever being pivoted to the upright l so as to give a sufficient preponderance to its inner or jointed end for the purpose, while its outer end has a cord and tassel, H, suspended from it so as to hang down in front of the blind, and thus afford the means for lifting its jointed end from between the teeth of the ratchet-wheel G as occasion may require. Near the cord end of the pawl-lever E there is a projection, e', (see fig. 2,) against which the upper end of the brake-bar F rests. The latter (F) is curved to fit the side of the roller A, and has its lower end jointed to the foot of the upright l, so that when the outer end of the pawl-lever E is pulled downward by means of the cord H, the projection e' thereof presses the brake-bar F against the roller A.

Operation: By pulling the cord C in a downward direction, rotary motion is given to the roller A, and thus the bands B B are wound up in the grooves a' a', and the slats D elevated successively from the bottom one upward, the jointed end of the pawl-lever E being lifted and passed by the teeth of the ratchet-wheel G; but when the cord C is released, the radial surface of any one of the teeth of the ratchet-wheel G catches against the pawl, and thus prevents the roller A from rotating in the opposite direction, and consequently holds the blind-slats in their elevated position. To lower the elevated slats, all that is necessary is to pull the cord H in a downward direction sufficiently to lift the pawl out of the ratchet-wheel teeth, and in order to prevent a sudden fall of the slats, the operator increases the strength of his pull on the said cord H, and thus presses the brake-bar F more firmly against the roller A, and controls the speed of the falling motion at will.

It will be seen that my improvement does away with the pair of cords and pulleys, and the requisite

hitching-hooks heretofore required for raising, staying, and lowering a Venetian blind, and gives a more perfect and facile control over the blind in operating it, and that the friction being less on the take-up bands B B on the roller A than the cords and pulleys heretofore used, they will be more durable, and the blind less liable to get out of order in use.

Having thus fully described my improvement, what I claim as new therein of my invention, and desire to secure by Letters Patent, is confined to the following, viz:

1. I claim the application to a Venetian blind of the roller A, in combination with the flat take-up bands B B, and the suspended operating-cord C, the said parts being constructed and applied to operate substantially as and for the purpose described.

2. I also claim, in combination with the subject-matter of the preceding clause, the application of the ratchet-wheel G, the jointed, gravitating pawl-lever E, the brake-bar F, and the suspended cord H, the same being constructed and applied to operate substantially as and for the purpose described.

GEORGE F. SMITH.
